(57) **CLAIM**

The ornamental design for a removable display for a water purifier, as shown and described.

DESCRIPTION

FIG. 1 is a front, right, top perspective view of a removable display for a water purifier.

FIG. 2 is a rear, left, bottom perspective view of the removable display for a water purifier of FIG. 1.

FIG. 3 is a front elevation view of the removable display for a water purifier of FIG. 1.

FIG. 4 is a rear elevation view of the removable display for a water purifier of FIG. 1.

FIG. 5 is a left side elevation view of the removable display for a water purifier of FIG. 1.

FIG. 6 is a right side elevation view of the removable display for a water purifier of FIG. 1.

FIG. 7 is a top plan view of the removable display for a water purifier of FIG. 1; and,

FIG. 8 is a bottom plan view of the removable display for a water purifier of FIG. 1.

1 Claim, 4 Drawing Sheets
